ROTARY WOOD CHIPPING MACHINE

Walter I. Brown, Oakland, Calif.

Application November 21, 1932, Serial No. 643,659

6 Claims. (Cl. 83—75)

This invention relates to rotary wood chipping machines.

My copending application for a method of and a device for forming pulp chips, filed November 21, 1932, Serial No. 642,758 relates to a machine of the reciprocating type in which only one block can be operated on at a time and which is very suitable for small production.

My present invention has for its principal object to provide a machine in which the number of blocks of wood operated on by the machine may be made of any desired number, and will produce large quantities of pulp chips which are uniform and equal in all dimensions. No feathered edges or thin portions are formed on the chips.

Where non-uniform chips are placed in respective pulp solutions, the thinner portions of the chips and the smaller chips are completely acted on before the heavier chips have had the reaction completed, and by the time the heavier chips have been fully acted upon, the smaller chips and thinner portions have become formed into a gelatinous mass having no utility in the manufacture of the particular product, but instead being a hindrance to the successful and efficient operation of the pulping unit.

The further object of this invention is to provide a machine for producing chips of uniform size with parallel faces from pulp wood, in large quantities, so that the chips produced will be acted on by the pulping solutions simultaneously and to the same degree, whereby losses are obviated due to the gelatinizing of smaller or thinner portions of chips.

Another object of the invention is to provide a machine for forming equi-dimensional wood chips in large quantities, the machine being adjustable to provide chips of desired thickness for the most efficient operation of the pulping unit.

A further object of the invention is to provide a machine of the class described which is of the rotary type, and in which a plurality of pulp wood blocks may be formed into pulp chips simultaneously, by constant rotation of the machine.

Other objects and advantages of the invention will become apparent as the following description is read on the drawings forming a part of this specification and in which similar reference characters are used to designate similar parts throughout the several views, of which:

Fig. 1 is a plan view of the rotary wood pulp machine.

Fig. 2 is a section taken on line 2—2 of Fig. 1.

Fig. 3 is a fragmentary plan view showing the

slitting and shearing units, the supporting and aligning means and the riders.

Fig. 4 is a section taken on line 4—4 of Fig. 3. Fig. 5 is a section taken on line 5—5 of Fig. 1.

Fig. 6 is a section showing a side elevation of one of the slitting cutters.

Fig. 7 is a section taken on line 7—7 of Fig. 6. The invention consists of a frame having legs

10 which are suitably braced at 11 and a central standard 12 forming a support for the bearing element, cross members 13 tying the legs 10 and central standard 12 into a unit to form the frame.

The legs 10 extend above the cross members 13, and have mounted adjacent the top, supporting elements in the form of grooved wheels 14, 15

these wheels having an angular groove formed about the periphery and being provided with adjusting means consisting of an eccentric shaft 15, the eccentric portion of which rotatably cooperates with the wheel 14, the shaft being secured against rotation by means of a lever 16 secured to the upper end of the shaft as indicated in Fig. 5, this lever being provided with an arcuate slot 17 for cooperation with a bolt or screw 18 secured in the bracket 19.

Rigidly mounted on the top of the legs and transversely spanning the frame are cross members 20, two sets of cross members being shown, although any number may be provided, these cross members forming supports for the hoppers 30 and for the central shaft bearing.

A bearing 21 is mounted on top of the central standard 12 and another bearing 22 is mounted and supported at the coincidence of the cross members 20, a rotary cutter-wheel being rotatably mounted between the bearings 21 and 22, the central shaft 23 being vertically disposed, so that the cutter-wheel rotates in a horizontal plane.

The cutter-wheel consists of two concentric rings 24 and 25 of different diameters supported by arms 26 which are integral with or fixedly secured to a central hub 27. The outer ring 24 or periphery of the cutter-wheel is angularly formed complementary to the grooved wheel 14, the groove in the wheel and the periphery of the ring 24 being formed divergently toward the axis of the cutter-wheel, cooperating in such manner as to retain the cutter-wheel at its rim against vertical deflection, and thus permitting movement only in a circular direction in a horizontal plane, the proper alignment of the cutter-wheel being very important, and for which purpose the adjustment of the grooved wheels 14 is provided.

Spanning the space between the inner ring 25

25 and outer ring 24 is a plurality of slitting and shearing units, consisting each of a bar or support 28 which is removably secured to the respective rings as indicated at 29, and which is 5 provided with a plurality of slitting cutters 30, these slitting cutters being equally spaced in a direction radially from the axis of the shaft 23 and being spaced at a distance equal to the length of the wood chips to be produced.

10 These slitting cutters consist of a knife 31 having a sharp leading edge and top edge and being secured in plugs 32 as indicated at 33, the plugs being secured in suitable apertures 34 by means of set screws 35 whereby the height of the 15 cutting edge above the surface 36 may be adjusted.

It will be noted that these slitting elements are readily replaced or removed for sharpening, and that the plates 28 may be provided with different spacing of the slitting elements so that the 20 length of the chips may be varied as desired.

Mounted in follow relation to the slitting elements is a shearing element or knife 37 having a flat top face 38 and a sharp front edge 39, and 25 which is supported by the rings 24 and 25 at such a height that the top surface 38 is substantially in a plane parallel to the top cutting edge of the knives 31, so that as the machine operates, the slitting cutters 31 will slit transversely through 30 the side of a block of wood, and the shearing element 37 will shear off the slit portion as indicated at 40, this sheared off portion dropping into a suitable receptacle or chute (not shown).

Riders 41, arcuately spanning the space between the shearing element 37 and the next following slitting element 28 are provided with uniform slope from the shearing element 37 to the slitting element 28, to support the block of wood between these elements and permit gravitational 40 feeding to the next following set of slitting knives, thereby preventing any rebound in the block or shock to the machine.

Driving means for the rotary cutter-wheel consists of a bevel gear 42, which is fixedly secured 45 to the underside of the cutter-wheel, and which has cooperating therewith a bevel pinion 43, which is fixed on a shaft 44, this shaft being rotatably mounted in bearings 45, the bearings being mounted on a suitable base 46 on the transverse members 13. The pinion 43 is driven by 50 means of a motor 47 and a plurality of these motors and drive pinions are preferably provided, to be equi-angularly spaced so as to obviate any tendency for distortion of the cutter-wheel and to equalize the thrust, thus maintaining the 55 accuracy of the slitting cutters and preventing the breaking thereof.

Mounted on the cross members 20 in cooperative relation to the slitting and shearing units 60 is a plurality of hoppers 48, of rectangular form, to slidably receive wood in the form of blocks as indicated at 49, to permit the block to gravitationally feed to the slitting knives 31 and shearing knife 37, these hoppers being so formed as 65 to prevent horizontal movement of the block while the slitting cutters are slitting the side of the block, while still permitting the downward movement.

The number of slitting and shearing units is 70 made different than the number of hoppers and should preferably vary by one, whereby the slitting and shearing units are successively brought into cooperation with the block of wood and thus distributing the power during operation of the machine.

The machine shown in the drawings is provided with four hoppers and five slitting and shearing units. However, this number may be increased as desired.

The operation of the machine is as follows: 5 The pulp wood is cut into rectangular blocks nearly equal in length to the radial lengths of the hoppers and of a thickness nearly equal to the transverse width of the hoppers, the height of the block being inconsequential. The cutter-wheel 10 or rotor is driven by means of the motors through the pinion 43 and bevel gear 42, the slitting knives 30 first cooperating with the block of wood and cutting a series of transverse slits across the bottom of the block, the shearing knife 38 next 15 cooperating with the block and shearing off the slitted portion, providing a plurality of chips of equal thickness and equal length, the chips falling away through the opening provided between the shearing cutter 38 and the mounting block 28. 20 Referring to Fig. 1, it will be noted that the slitting and shearing unit 50 has just completed the operation of the block 51, that the slitting and shearing element 52 is in cooperation with the block 53, and that after it passes out of cooperation and has completed the operation, the slitting and shearing element 54 will cooperate with the block 55, the operation of the various units being successive, thereby equalizing the load during the 25 operation of the machine.

Having described an operative rotary machine for forming equi-dimensional pulp chips, it will be understood that variations in construction and arrangement of parts which are consistent with the appended claims may be resorted to 30 without detracting from the spirit or scope of the invention or sacrificing any of the advantages thereof.

I claim:

1. A wood chipping machine comprising a supporting frame, a cutter wheel rotatively supported by said frame, said cutter wheel consisting of concentrically disposed ring-like members, means on said cutter wheel for supporting a series of slitting cutters arranged in a radial line with respect to the axis of rotation of the cutter wheel, support arms carried by the cutter wheel and arranged concentrically with respect to said ring-like members, a shearing knife mounted on the forward ends of said support arms in a position adjacent to said slitting cutters, means for rotating said cutter wheel, and one or more wood hoppers supported by said frame in position to feed wood to said slitting cutters and shearing knife. 40

2. A wood chipping machine comprising a supporting frame, a cutter wheel rotatively supported by said frame, means for rotating said wheel, a series of slitting cutters arranged radially on said cutter wheel, a blade supporting device arranged concentrically with respect to said cutter wheel, a radially disposed shearing blade carried by the blade-supporting device in a position adjacent said slitting cutters, and means for feeding a block of wood to said blade and cutters. 60

3. A wood chipping machine comprising a supporting frame, a cutter wheel rotatively supported by said frame, said wheel consisting of concentrically disposed ring-like members, means for rotating said wheel, one or more radially disposed support bars secured to said ring-like members, a plurality of slitting cutters carried by each support bar and arranged radially with respect to said wheel, one or more radially disposed shearing knives carried by the support bars, there be- 70

ing one shearing knife for each support bar, the cutting edge of said knife lying adjacent to the slitting cutters of an adjacent support bar, and means normally fixed with respect to said cutter wheel for feeding wood to said knife and slitting cutters.

4. A wood chipping machine comprising a supporting frame, a cutter wheel, means carried by said frame for rotatively supporting said cutter wheel, said cutter wheel consisting of concentrically disposed ring-like members, a radially disposed support bar carried by the cutter wheel, a plurality of slitting cutters carried by the support bar and arranged radially with respect to the cutter wheel, arcuate arms secured to said cutter wheel and arranged concentrically with respect to said ring-like members, a shearing knife carried by said arcuate arms in a radial position adjacent to said slitting cutters, means for rotating said cutter wheel, and means for feeding wood to the shearing knife and slitting cutters.

5. A wood chipping machine comprising a supporting frame, a cutter wheel consisting of a pair of fixedly related concentric rings, means carried by the frame for supporting said wheel, means for rotating said wheel, a plurality of radially disposed support bars carried by said ring-like members in radial positions, a plurality of slitting cutters carried by each support bar, and arranged radially with respect to said wheel, means for ad-

justing said cutters in said support bars, arcuate arms secured to and extended forwardly from each support bar and arranged concentrically between said ring-like members, shearing blades carried by the forward ends of the arcuate arms, each shearing knife being located to the rear of a series of slitting cutters and arranged radially with respect to the cutter wheel, and means for feeding wood to the shearing knives and slitting cutters.

6. A wood chipping machine comprising a supporting frame, a cutter wheel formed with two concentric ring-like members, eccentric shafts rotatively mounted in said frame, support wheels mounted on said shafts and engaging the periphery of the cutter wheel in such manner as to rotatively support the same, means for rotatively adjusting said shafts so as to move the supporting wheels toward and from the periphery of the cutter wheel, a series of slitting cutters supported by said ring-like members and arranged radially with respect to said cutter wheel, a blade supporting device arranged concentrically with respect to said ring-like members, a radially arranged shearing blade carried by the supporting device and arranged adjacent to but to the rear of the slitting cutters, and means for feeding wood to said blade and said cutters.
